UNITED STATES PATENT OFFICE.

HERBERT H. HILLMAN, OF GRAND HAVEN, MICHIGAN, ASSIGNOR TO CHALLENGE REFRIGERATOR COMPANY, OF GRAND HAVEN, MICHIGAN, A CORPORATION OF MICHIGAN.

REFRIGERATOR AND THE LIKE.

Original application filed September 17, 1928, Serial No. 220,228. Divided and this application filed August 17, 1928. Serial No. 300,183.

The present invention relates to hingedly-mounted door or closure constructions and more particularly to such constructions as are for use in conjunction with refrigerators and 5 the like.

The main objects of this invention are to provide an improved form of construction of the character above specified; to provide improved means for securing overlaid metallic 10 sheet casing members to wooden bodies or frames of swinging doors or closures; and, to provide wooden body or frame door members concealed and protected by overlaid ornamental metallic sheet casings. The invention 15 shown and described herein is divided out of my co-pending application Serial No. 220,228, filed September 17, 1928 for "Refrigerators and the like."

An illustrative embodiment of the present 20 invention is shown in the accompanying drawings, in which:—

Figure 1 is a view in perspective of a refrigerator, parts of the metallic sheet casing being broken away to show the wooden frame 25 or body portion;

Figure 2 is an inner side view of one of the door closures therefor;

Figure 3 is a sectional view of said closure taken on the line 3—3 of Figure 2; and

Figure 4 is another sectional view of said closure taken on line 4—4 of Figure 2.

In the embodiment of the invention illustrated herein, the refrigerator has a wooden body, box or frame, comprising a top 1, back 35 (not shown), sides 3, bottom (concealed from view), and front 5. The front 5 is provided with rectangular openings closable by doors 6, 7 and 8 hingedly mounted at 9, 10 and 11 respectively.

These doors comprise wooden body or 40 frame members 12 whose outer surfaces are overlaid and concealed, ornamented and protected, by metallic sheet casing members 13.

These casing members are each provided with an inwardly-extending peripheral flange 14 45 which surrounds the wooden body of the door. This flange 14 has, at the free or outward corners of the door, an overhanging portion 15 underneath which said corners are received, as is shown in Figures 2 and 3. 50 These door members are secured in place in any suitable manner as by screws 16 which may be also used to mount the hinges 9, 10 and 11 upon the doors. Latches 17 and their keepers 18 provide means for opening and 55 locking the swinging door members.

It will thus be seen that the improved construction herein described and shown provides novel means for securing metallic sheet casing members to wooden bodies or frames 60 and that such construction may be well applied to swinging doors for refrigerators and the like.

Although but one specific embodiment of the invention has been herein shown and described it will be understood that numerous 65 details thereof may be altered or omitted without departing from the spirit of the invention defined in the following claim.

I claim:

In a structure of the class described, having a door opening, a hinged closure for said opening having a body and being provided with corners, a casing for said body having an inwardly extending peripheral flange, and a 75 rebent web integral with and bridging the peripheral flange at the corners thereof at one edge of the closure to form pockets receiving the corners of the body member, and a hinge on the opposite edge of the closure for swing- 80 ingly mounting the same and for securing the casing to the body.

In testimony whereof I have hereunto set my hand at Grand Haven, Michigan, this 11th day of August, 1928.

HERBERT H. HILLMAN.
